UNITED STATES PATENT OFFICE.

JOHN T. F. MACDONNELL, OF HOLYOKE, MASSACHUSETTS.

PAPER-MAKING MACHINE.

SPECIFICATION forming part of Letters Patent No. 320,372, dated June 16, 1885.

Application filed September 23, 1884. (No model.)

To all whom it may concern:

Be it known that I, JOHN T. F. MACDONNELL, of Holyoke, in the county of Hampden and State of Massachusetts, have invented 5 certain Improvements in Paper-Making Machinery, of which the following is a specification.

The aim of my invention is to secure the production by paper-making machines of a 10 web or sheet of uniform weight.

To this end it consists in the employment, in connection with a paper-making machine, of 15 automatic mechanism for maintaining a uniform consistency of the stock, and automatic mechanism by which the stock of uniform consistency is delivered to the machine at a rate corresponding with the speed of the machine.

In the manufacture of paper the rags or 20 other material, properly cut or ground to a fine consistency and combined with water, constitutes the pulp which is fed to the machine. In order to secure a uniformity of the 25 weight or thickness of the paper produced, it is necessary that the pulp shall not only be of a uniform consistency, but also that it shall be delivered to the machine with greater or less rapidity, according to the speed at which the machine is driven. Neither uniformity in the consistency of the pulp nor a graduation 30 of the rate of delivery to the machine will be alone sufficient to secure uniform results. The regulation of the consistency and the regulation of the feed are both necessary to the end in view, and are dependent each upon the other.

In carrying out my invention I deliver the 35 pulp from a chest or receptacle to an automatic mechanism by which its consistency is regulated, and from which it is delivered of an unchanging consistency to a feed mechanism, from which it passes to the paper-machine. This valve or other feed-controlling device by 40 which the rate of delivery is increased or diminished is connected with and controlled by the paper-machine, so that as the speed of the machine decreases the delivery of the pulp thereto will be increased to correspond, and vice versa.

For the purpose of regulating the consistency of the pulp, I propose to make use of a 45 mechanism similar to that described in Letters Patent of the United States granted to me on the 27th day of May, 1879, No. 215,946,

or any equivalent mechanism, several of which are shown in the drawings.

For the purpose of controlling the feed, I 55 prefer to employ a sliding gate operated by a governor connected by suitable gearing, either directly or indirectly, with the paper-machine; but other feed-controlling devices, several of which are hereinafter described, may be used. 60

Referring to the drawings, Figure 1 is an elevation partly in section, showing my mechanism introduced for action between the stuff-chest and the paper-machine. Fig. 2 is a horizontal section on the line $x-x$, showing the 65 arrangement of valves for regulating the delivery of the material to the machine. Fig. 3 is a sectional modification on the line $z-z$ of Fig. 2. Figs. 4 and 5 are views of a circular regulating-valve. Fig. 6 is an outline or dia- 70 grammatic view illustrating modified forms of the invention. Fig. 7 is a top plan view of one of the mechanisms represented in the preceding figure.

Referring to Figs. 1, 2, and 3, A represents 75 a stuff box or reservoir. The stock is pumped from the main chest into the stuff-box in the ordinary manner. Near one side the stuff-box contains a vertical partition, a , rising from the bottom to a point near the top. The pulp 80 flowing over the top of this partition descends on the opposite side and escapes near the bottom of the box, through a conductor, B, into a receptacle, C. The receptacle C is suspended from one end of a balanced lever or scale-beam, 85 D, which is weighted or balanced in such manner that it will remain in equilibrium when the receptacle C is filled to the proper height with pulp of the proper consistency. The receptacle C contains a vertical partition, b , ex- 90 tends from a point near the top to a point near the bottom. The pulp entering on one side of this partition passes thereunder and escapes from the opposite side, near the top, through an overflow-spout, c. This construction maintains the pulp at a uniform height 95 within the receptacle.

As the specific gravity of the pulp varies according to its consistency, it follows that any change in the consistency will destroy the equilibrium and cause the receptacle C to descend or ascend, as the case may be.

To one side of the receptacle I attach an arm, d, connecting with the spindle e of a valve, f,

which controls the delivery of water through the pipe E into the spout or conductor B, through which the pulp is delivered from the stuff-box into the receptacle. The specific gravity of the stock is greater than that of the water. When, therefore, the consistency of the pulp in the receptacle becomes too thick, the resulting depression of the receptacle causes the valve to be opened and water to be admitted through the pipe to the receptacle until the pulp is reduced to the proper consistency, whereupon, the equilibrium being again established, the receptacle rises and the flow of water diminishes or ceases. In this manner the pulp is delivered from the receptacle C of a constant unvarying consistency, the operation being essentially the same as that set forth in my patent before referred to. The pulp flowing from the receptacle C is received in a stationary receptacle, F, provided with an overflow-pipe, G, by which the body of pulp is maintained at a constant height therein. This regulation of the height or head of the pulp within the receiver F is important, in that it insures a uniform delivery when the outlet-valve is at a given adjustment. In the bottom of the receiver F there is an outlet-port, g, through which the pulp descends to the conductor leading to the paper-machine. This opening is closed by means of two horizontally-sliding valves, H and I, moving at right angles to each other, and one above the other, the first-named valve being designed for adjustment by hand, while the second is operated automatically in the manner which will presently be described. A screw rod, J, mounted in suitable fixed bearings, engages at one end with the valve I, and is provided at the opposite end with a spur-wheel, K. This wheel is acted upon and turned in one direction or the other by two arms or pawls, L and M, applied to a reciprocating bar, N, which is mounted in a revolving head or post, O, and connected with the inner ends of the weighted arms P, the device being similar in this regard to the ordinary ball-governor. The rotary head is connected by miter gear with a shaft, Q, carrying a pulley, R, which is connected by a belt with the paper-machine or with the mechanism through which motion is communicated to said machine, so that the governor will receive a speed corresponding precisely with that of the paper-machine. As the speed of the paper-machine increases, the corresponding increase in the speed of the governor will cause the arms P to be thrown outward by centrifugal force, the effect of which will be to depress the bar N and cause the dog L to turn the screw J, and thereby open the valve I, so as to permit the pulp to flow more rapidly to the machine. A decrease in the speed of the machine is followed by an elevation of the bar N and a closing of the valve I to a corresponding extent, so that the rate of delivery of the pulp is reduced to correspond with the speed of the machine.

From the foregoing it will be understood

that by my combination of mechanism to regulate the consistency and mechanism to regulate the rate of delivery I am enabled to supply the paper-machine automatically with pulp uniform in consistency and variable in quantity, according to the rate of the machine. The result is the production of paper of perfect uniformity in weight and thickness.

75

While I have described those details of construction which I consider the best adapted for practical purposes, it will be manifest to the skilled mechanic that the regulator and the valve controlled thereby may be modified in detail, and that the regulator may be connected with the paper-machine by driving mechanism of any appropriate character.

80

It is to be noted as a peculiarity of my automatic feed mechanism that the supply of material to the machine is constant, and that in this regard it differs essentially from mechanisms in which pumps, buckets, and equivalent mechanisms deliver material intermittently.

90

In place of the overflow-pipe G, or in addition thereto, for the purpose of maintaining a uniform height of the pulp in the receiver F, I propose to employ therein a float, S, suspended from one end of a lever, T, the opposite end of which serves to raise and lower arms or pawls U-V, mounted to slide on a vertical rotary shaft, W, driven through intermediate gearing from the paper-machine. As the pawls are raised or lowered, one or the other will engage with a spur-wheel, X, attached to a screw, Y, which controls a valve, Z, for regulating the delivery of the material from the stuff-box A.

95

In place of the two independent valves moving at right angles to each other, as before described, to regulate the feed, I may employ a valve, either flat or circular, movable in two directions at right angles to each other over a throat or passage corresponding in form and size to the valve-opening, the movement in one direction to be effected by hand and in the other direction by the automatic governor. Figs. 4 and 5 represent this construction embodied in a circular valve. a' represents the cylindrical valve body or case, provided with the rectangular port b'. I represents the valve, made of circular form and adapted to slide in an axial direction, and also to rotate within the body a'. The valve is provided with a transverse rectangular port or opening corresponding to that of the shell. When the two openings correspond, the valve will deliver its full capacity; but moving the valve either axially or in a rotary direction will have the effect of throwing the ports out of register to a greater or less extent, and thus reducing the flow of material. The valve is provided with a spindle, c', which may be moved longitudinally by hand, and is also provided with a spur-wheel, d', engaging a worm, e', the shaft of which is provided with a spur-wheel, K, adapted to be actuated by the governor in the same manner as represented in the preceding figures. Changes in the speed of the paper-machine

135

will cause the worm to rotate the valve, and thus open or close its port, controlling the rate of delivery according to the speed of the machine. The arbitrary changes in the rate of delivery to secure the proper thickness of the sheet are effected by pushing the spindle endwise. It will be observed, that this valve, is the mechanical equivalent of the two valves H and I, moving at right angles to each other, 10 the variations in the size of the port or passage being effected in essentially the same manner in the two cases.

Referring to Fig. 6, it will be found to represent substantially that arrangement of parts which are commonly used for supplying pulp to a paper-machine with my improved devices embodied therewith in various forms. In this case, A' represents the engine or beater, in which the stock is constantly agitated by 15 means of a revolving wheel or cylinder. B' represents a spout conducting the stock from the engine into a stuff-chest, C, provided with rotary beaters. This stuff-chest is connected at its bottom by a delivery-pipe, D', provided 20 with a force-pump or equivalent device, to a stuff-box, E', from which a pipe, F', returns the surplus material to the stuff-box, as usual. From the stuff-box E' the stock flows through 25 the pipe F'' by way of a fan pump, G', and a spout, H', into what is commonly known as a "mixing-box," I', whence it is delivered through a screen, J', to the paper-machine proper. In applying my improvements to an apparatus thus organized I may secure the uniform consistency of the stock by mounting the tank or 30 body of the engine A' on a counterbalanced lever, K', so that it will rise or fall according to the specific gravity of its contents, which should remain at a constant level therein. A 35 pipe, L', supplies water to the engine for reducing the pulp, while a second pipe, M', serves to discharge the surplus water. The two valves are provided with cocks, which are connected, respectively, by links N', to the reservoir of the engine, so that as the latter rises 40 and falls it will effect the automatic opening and closing of the respective valves, thus controlling the admission and discharge of the water in such manner as to maintain an un- 45 changing consistency of the stock; or, in place of regulating the consistency of the stock at the engine, as above described, I may introduce between the stuff box and the mixing-box a receiving-vessel, O', arranged to receive material directly from the stuff box, and provide it with an overflow-pipe, P', for returning the surplus material to the stuff-chest, whereby the constant level of the material is 50 maintained in the receiver. The pipe L' serves 55 to deliver water into the receiver for the purpose of reducing the consistency of the stock. Within the receiver there are two floats, Q' and R', the former arranged to float at all 60 times upon the surface, while the latter is of such buoyancy that although it will float upon the surface when the stock is of the proper 65 consistency it will sink below the surface.

when the consistency or specific gravity is reduced. The two floats are connected by cords passing over guide-pulleys with opposite ends of a lever, S', so that the sinking of either float must be followed by the rising of the other. The guide-pulleys for the cords are mounted in opposite ends of a centrally-pivoted lever, T', so that the sinking of either weight is accompanied by a depression of the corresponding end of the lever. At one end the lever is connected by a link, U', in the water pipe V'. When the pulp becomes too thin, the float R' will sink, depressing one end of the lever T', opening the valve W', and admitting water until the proper consistency is again established.

In place of the foregoing arrangement, the regulation of the stock may be effected in the mixing-box I' by placing therein a float, Q', adapted to float on the surface of the pulp when it is of the proper consistency, and connecting this float by an intermediate lever with a water-admission valve, W''; or a flexible diaphragm from which the pulp flows may be so combined with valve mechanism that, sinking beneath the weight of the heavy pulp, it will cause the water admission valve to be opened.

The foregoing are mentioned as examples of the various forms which my invention may assume in practice.

While the feed mechanism or mechanism for controlling the rate of delivery of the machine represented in Figs. 1 to 4 answers an excellent purpose, it may sometimes be found advisable to use the rotary feeder, such as represented at X', Figs. 6 and 7. This consists of a cylinder revolving beneath the mouth of the receptacle, O', which is closed thereby. The feeder is provided in its periphery with a number of cells or pockets, which are carried beneath the mouth of the receiver, and thus past the mouth of the pipe Y', which communicates with the fan-pump. Each 110 cell or pocket in passing the receiver is filled therefrom, the stock in the pocket being carried forward by the rotation of the feeder and discharged into the pipe Y'.

In order to effect the arbitrary regulation 115 of the amount of stock delivered, I propose to provide the revolving feeder X' at one end with a plate, Z', adjusted in the direction of the axis by a central screw, and provided with blocks or arms which enter the ends of the 120 cells or pockets, as shown in Fig. 7, so that by turning the screw the capacity of the pocket may be increased or diminished at will.

Having thus described my invention, what I claim is—

1. In combination with each other and with a paper-machine, an automatic mechanism controlled by the specific gravity of the stock to regulate its consistency and an automatic feed mechanism connected with a mechanical governor and with a paper-machine, whereby stock may be delivered to the paper-machine of uniform consistency and at a speed corresponding to the speed of the machine.

2. The herein-described feeding apparatus for a paper-machine, comprising, first, the balanced receptacle connected with a water-supply valve, and, second, a hopper or receptacle supplied from the balanced receptacle and provided with a valve to regulate the discharge, and with a mechanical governor connected to said valve, said parts being constructed and arranged for joint operation substantially as hereinbefore set forth.

3. The combination, substantially as hereinbefore described and shown, of a paper-machine, an automatic feed mechanism controlled by the machine to regulate the rate of delivery of the stock, and an automatic mechanism to produce a uniform consistency of the stock delivered to the feed mechanism.

4. In combination with a paper-machine, an elevated receiver or hopper, from which the stock flows constantly downward to the machine, means, substantially as described, to maintain a constant head or pressure of stock within the hopper, a gate to regulate the flow of stock from the hopper, and an automatic mechanical governor connecting the paper-machine with the gate, substantially as described, whereby the delivery of stock is controlled in accordance with the speed of the machine.

5. In combination with a paper-machine and a hopper or source of stock-supply having a constant delivery to the machine, a feed mechanism, and mechanism, substantially as described, connecting the gate with the ma-

chine, whereby the rate of delivery is varied 35 in exact conformity to the rate of the machine.

6. The feed spout or conductor and the feed-controlling valve or valves adapted for adjustment in one direction by hand, in combination with a mechanical governor adapted 40 for connection with the paper-machine, whereby the rate of feed may be regulated according to the speed of the machine, and also regulated at will to increase or diminish the thickness of the web.

7. In combination with a paper-machine, the rotary head O, centrifugally-acting weights, P, bar H, and the feed-regulating valve connected with said bar by means substantially such as described.

8. In combination with the gate and the screw for adjusting the same, the rotary shaft W, provided with arms U and V, and the float S, connected with said arms by means substantially as described, whereby the rising and falling of the float are caused to reverse the action of the valve-operating device.

9. In combination with the valve I, screw J, and wheel K, the rotary centrifugal governor having the bar N, provided with dogs L 60 and M.

In testimony whereof I hereunto set my hand, this 23d day of August, 1884, in the presence of two attesting witnesses.

JOHN T. F. MACDONNELL.
